By Leslie W. Frick
Attorney.

UNITED STATES PATENT OFFICE.

ROLANDIS A. BLAIR, OF FORT WAYNE, INDIANA, ASSIGNOR TO THE P & M COMPANY, OF CHICAGO, ILLINOIS, A CORPORATION OF ILLINOIS.

RAIL ANCHOR.

Application filed October 20, 1924. Serial No. 744,545.

To all whom it may concern:

Be it known that I, ROLANDIS A. BLAIR, a citizen of the United States, residing at Fort Wayne, in the county of Allen and State of Indiana, have invented certain new and useful Improvements in Rail Anchors, of which the following is a specification.

My invention relates to devices for preventing the longitudinal creep of railroad rails, these devices being commonly called rail anchors, anti-creepers or rail stays.

One of the objects of my invention is the provision of a rail anchor of simple and compact construction, requiring a minimum amount of metal, inexpensive to manufacture, which will maintain a reliable hold on the rail as against the tendency of the device to become loosened by vibration or other disturbing influences, and which may be quickly and conveniently put in place on the rail, or removed therefrom, if occasion requires.

A further object of my invention is the provision of a rail anchor so constructed that it may be removed and replaced several times without impairing its holding power.

It is another object of my invention to provide a rail anchor adapted to prevent the longitudinal creep of railroad rails in both directions.

A further object of my invention is to provide a rail anchor so constructed that it can be applied properly by any ordinary track laborer.

Another object of my invention is the provision of a rail anchor so constructed that any tendency for the anchor to move obliquely on the rail base or to tilt out of its normal vertical plane will only serve to increase the grip of the device on the rail base.

It is another object of my invention to provide a rail anchor so constructed that it will have a very substantial and effective foot-piece to bear against the side of a tie, or the like, without, however, appreciably increasing the amount of metal in the device.

Another object of my invention is to provide a rail anchor so constructed that it cannot be accidentally knocked off the rail; also so constructed that there will be no parts projecting any substantial distance at

either end of the device, above the rail base flanges to cause an obstruction.

A further object of my invention is to provide a rail anchor having all the advantages above noted and which may be formed in one piece from a bar of resilient material.

The invention consists in the novel constructions, arrangements and devices to be hereinafter described and claimed for carrying out the above-stated objects and such other objects as will appear from the following description of a preferred embodiment illustrated in the accompanying drawings, wherein—

Fig. 1 is a perspective view of a rail anchor embodying the principles of my invention applied to a fragmentary portion of a rail base;

Fig. 2 is a side elevational view of the anchor showing in dotted lines its first position and in full lines its second position in the application of the anchor to the rail base;

Fig. 3 is a side elevational view of the anchor showing in dotted lines its third position in its application to the rail base and showing in full lines its final position on the rail base; and

Fig. 4 is an end elevational view of the anchor showing it positioned on the rail base and against a tie.

Like characters of reference designate like parts in the several views.

Referring now to the drawings, it will be noted that the embodiment therein illustrated is formed of a bar of resilient steel formed so as to provide a straight portion 8 adapted to extend transversely under a rail base and having at one end an upwardly extending return disposed arm 9 and at its other end an upwardly extending angularly disposed arm 10. The arm 9 is provided with a recess, the end wall 11 of which provides a bearing surface adapted to engage the vertical edge 12^a of the rail base flange 12. The upper wall of the said recess is defined by an inwardly extending relatively wide lip 13 and the lower wall is defined by a narrow lip 14, said lips being adapted to engage the respective top and bottom surfaces 12^b and 12^c of the base flange 12 when the device is in gripping position on the rail. The arm 10 is pro-

vided with a recess having a bearing surface 15 which is adapted to engage the vertical edge 16^a of the rail base flange 16. The arm 10, above the surface 15, is provided with an inwardly extending lip 17 which is adapted to engage the top surface 16^b of the base flange 16 when the device is in gripping position on the rail. The arm 10 on its inner side below the bearing surface 15 is also provided with an inclined surface 18 which is adapted to ride over the edge of the rail base flange 16 as the device is applied to or removed from the rail, as will be presently explained.

15 The several parts of the device are so formed that the normal distance between the bearing surfaces 11 and 15, represented by the line "x" Fig. 2, is considerably less than the width of the rail base to which the 20 device is to be applied, while the distance between the inner edge of the lip 17 and the bight 19 between the arm 9 and the transverse portion 8, represented by the line "y" Fig. 2, also the distance between the 25 inner face of the lip 14 and the bight 20 between the arm 10 and the transverse portion 8, represented by the line "z" Fig. 2, are greater than the width of the rail base to which the device is to be applied. The 30 lines "x" and "z" are applied to the full-line representation in Fig. 2, whereas line "y" is applied to the dotted line representation to more clearly show the length indicated by this line with relation to the width of the 35 rail-base.

In applying the device to the rail the device is brought into a position substantially as shown in dotted lines in Fig. 2 with the arm 9 hooked over one of the rail base 40 flanges, in the present showing over the base flange 12, the edge of said base flange extending into the bight 19. The lip 17 will now readily clear the outer edge of the base flange 16 so that the end of the device 45 carrying the arm 10 may be raised to bring the transverse portion 8 substantially parallel with the rail base. The device may now be shifted laterally on the rail base to bring the edge of the base flange 16 into 50 the bight 20 whereupon the lip 14 will clear the edge of the base flange 12 in the manner shown in full lines in Fig. 2, so as to permit the device to be moved to the dotted line 55 position of Fig. 3. By striking the upper end of the arm 10 with a sledge or the like, the end of the device carrying said arm 10 may be forced down, the inclined surface 18 riding down over the edge 16^a of the base flange 16 forces the arms 9 and 10 apart until 60 the bearing surface 15 engages the vertical edge 16^a of said base flange and the recessed end of arm 9 is in firm engagement with the top, bottom and vertical surfaces of the base flange 12, the final position of the 65 device on the rail base being as shown in full

lines in Figs. 1 and 3. In Fig. 4, the device is shown as abutting against a tie 21 and being adapted to prevent creepage of the rail in the direction indicated by the arrow.

The upwardly extending arms 9 and 10 are quite short and since the distance between the bearing surfaces 11 and 15 is substantially less than the width of the rail base, it will be obvious that the device, in being applied to the rail, is placed under a very considerable tension or strain, consequently, the arms exert a powerful grip on the edges of the respective rail base flanges. As the end of the device carrying the arm 10 is forced down relatively to the rail base, the inclined surface 18 in riding over the edge of the base flange 16 tends to produce a furrow or groove in the base flange and interfitting vertical ridges and grooves are formed in the co-engaging surfaces of the bearing 15 and the edge of said base flange. The powerful grip of the device on the rail and the character of the co-engaging surfaces of the bearing 15 and the base flange 16 are ample to prevent any slippage of the device longitudinally of the rail in either direction notwithstanding the disturbing influences to which a device of this kind is subjected such, for example, as the passage of heavy rolling stock and changeable weather conditions. It will be obvious that any tendency of the device to be forced obliquely on the rail base will only tend to increase the distance between the bearing surfaces 11 and 15 and, consequently, increase their grip upon the edges of the respective rail base flanges. Since the lips 13 and 14 engage the respective top and bottom surfaces of the base flange 12 and the lip 17 engages the top surface of the base flange 16, all tendency for the device to tilt out of its normal vertical plane is reduced to a minimum. However, any tendency for the device to tilt out of its vertical plane must necessarily be accompanied by a tendency for the lip 14 to ride up into engagement with the vertical edge 12^a of the base flange 12 which would produce a greater strain in the device due to forcing further apart the bearing surfaces 11 and 15 with the consequent result that the device exerts a greater gripping action on the rail base.

The device is of very simple and compact construction requiring a minimum amount of metal and may be inexpensively manufactured in one piece from a bar of suitable resilient metal. The device is adapted to prevent longitudinal creep of rails in either direction. It may be applied on a rail base from either side, in other words, it is immaterial which flange of the rail base the return disposed arm 9 is hooked over. The device can only be applied to a rail in one way and it may be conveniently, quickly

and properly applied by any ordinary track laborer capable of driving a spike. The device may be readily removed from the rail by forcing upwardly the end carrying the 5 angularly disposed arm 10 which may be done either by prying upwardly that end of the device while the rail base flange 16 is tapped with a hammer adjacent the arm 10 or by striking the under side of the left 10 end of the device with a sledge or the like. The device may be reapplied to a rail, in fact, it may be removed and replaced several times without impairing its holding power.

15 It will be noted that the transversely extending portion 8 of the device is disposed a substantial distance below the base of the rail, in other words, there is a substantial 20 space between the upper side of the portion 8 and the under side of the rail base, which arrangement results in a substantial and effective footpiece to bear against the side of the tie and which is obtained with practically no appreciable increase in the amount 25 of metal in the device. No part of the device projects any substantial distance above the rail base flanges; therefore, the device offers practically no obstruction to interfere with track work or over which trackmen or 30 trainmen might stumble. The device cannot be accidentally knocked off the rail by any falling object or a misapplied blow from a sledge as in driving a nearby spike, because in loosening the grip of the device 35 on the rail the force must be such as to result in the end of the device carrying the arm 10 being forced upwardly relatively to the rail base.

I do not intend to limit my invention to 40 the details of construction shown and described, except only in so far as certain of the appended claims are specifically so limited, as it will be obvious that modifications may be made without departing from the 45 principles of my invention.

I claim:

1. A rail anchor comprising means 50 adapted to extend transversely under a rail base and having upwardly extending return disposed arm means at one end and upwardly extending angularly disposed arm means at the other end, said arm means having bearing surfaces adapted to grip the edges of the respective rail base flanges and being so arranged that the distance 55 normally between said bearing surfaces is less than the width of the rail base.

2. A one-piece rail anchor formed of 60 resilient material and comprising a portion adapted to extend transversely under a rail base and having an upwardly extending return disposed arm at one end and an angularly disposed arm at the other end, said arms having bearing surfaces adapted 65 to grip the edges of the respective rail base

flanges, said arms being so arranged that the distance normally between said bearing surfaces is less than the width of the rail base.

3. A rail anchor comprising means 70 adapted to extend transversely under a rail base and having upwardly extending return disposed arm means at one end and upwardly extending angularly disposed arm means at the other end, said arm means having bearing surfaces adapted to grip the edges of the respective rail base flanges and being so arranged that the distance normally between said bearing surfaces is less than the width of the rail base, said arm means at one end having lip means 75 adapted to bear on the top surface of the adjacent rail base flange, for the purpose specified.

4. A one-piece rail anchor formed of resilient material and comprising a portion 80 adapted to extend transversely under a rail base and having an upwardly extending return disposed arm at one end and an angularly disposed arm at the other end, said arms having bearing surfaces adapted to grip the edges of the respective rail base flanges, said arms being so arranged that the distance normally between said bearing surfaces is less than the width of the rail base, one of said arms having a lip adapted 85 to bear on the top surface of the adjacent rail base flange, for the purpose specified.

5. A rail anchor comprising means 90 adapted to extend transversely under a rail base and having upwardly extending return disposed arm means at one end and upwardly extending angularly disposed arm means at the other end, said arm means having bearing surfaces adapted to grip the edges of the respective rail base flanges and being so arranged that the distance normally between said bearing surfaces is less than the width of the rail base, each of said arm means having lip means 95 adapted to bear on the top surface of the adjacent rail base flange, for the purpose specified.

6. A one-piece rail anchor formed of resilient material and comprising a portion 100 adapted to extend transversely under a rail base and having an upwardly extending return disposed arm at one end and an angularly disposed arm at the other end, said arms having bearing surfaces adapted to grip the edges of the respective rail base flanges, said arms being so arranged that the distance normally between said bearing surfaces is less than the width of the rail base, each of said arms having a lip adapted 105 to bear on the top surface of the adjacent rail base flange, for the purpose specified.

7. A rail anchor comprising means 110 adapted to extend transversely under a rail base and having upwardly extending return disposed arm means at one end and upwardly 115 extending angularly disposed arm means at 120

the other end, said arm means having bearing surfaces adapted to grip the edges of the respective rail base flanges and being so arranged that the distance normally between said bearing surfaces is less than the width of the rail base, said arm means at one end having lip means adapted to engage the respective top and bottom surfaces of the adjacent rail base flange, for the purpose specified.

8. A one-piece rail anchor formed of resilient material and comprising a portion adapted to extend transversely under a rail base and having an upwardly extending return disposed arm at one end and an angularly disposed arm at the other end, said arms having bearing surfaces adapted to grip the edges of the respective rail base flanges, said arms being so arranged that the distance normally between said bearing surfaces is less than the width of the rail base, one of said arms having spaced lips adapted to engage the respective top and bottom surfaces of the adjacent rail base flange, for the purpose specified.

9. A rail anchor comprising means adapted to extend transversely under a rail base and having upwardly extending arm means at its respective ends which are provided with bearing surfaces adapted to grip the edges of the respective rail base flanges, said arm means being so arranged that the distance normally between said bearing surfaces is less than the width of the rail base, the arm means at one end having lip means adapted to engage the respective top and bottom surfaces of the adjacent rail base flange and the arm means at the other end having lip means adapted to bear on the top surface of the rail base flange adjacent thereto but being open at the bottom to permit the bearing surfaces of the anchor to exert a maximum gripping force on the rail base, for the purpose specified.

10. A one-piece rail anchor formed of resilient material and comprising a portion adapted to extend transversely under a rail base and having an upwardly extending arm at each end, said arms having bearing surfaces adapted to grip the edges of the respective rail base flanges, said arms being so arranged that the distance normally between said bearing surfaces is less than the width of the rail base, one of said arms having spaced lips adapted to engage the respective top and bottom surfaces of the adjacent rail base flange and the other of said arms having a lip adapted to bear on the top surface of the rail base flange adjacent thereto but being open at the bottom to permit the bearing surfaces of the anchor to exert a maximum gripping force on the rail base, for the purpose specified.

11. A rail anchor comprising means adapted to extend transversely under a rail

base and having upwardly extending return disposed arm means at one end and upwardly extending angularly disposed arm means at the other end, said arm means having bearing surfaces adapted to grip the edges of the respective rail base flanges and being so arranged that the distance normally between said bearing surfaces is less than the width of the rail base, the arm means at one end having lip means adapted to engage the respective top and bottom surfaces of the adjacent rail base flange and the arm means at the other end having lip means adapted to bear on the top surface of the rail base flange adjacent thereto but being open at the bottom to permit the said bearing surfaces to exert a maximum gripping force on the rail base, for the purpose specified.

12. A one-piece rail anchor formed of resilient material and comprising a portion adapted to extend transversely under a rail base and having an upwardly extending return disposed arm at one end and an angularly disposed arm at the other end, said arms having bearing surfaces adapted to grip the edges of the respective rail base flanges, said arms being so arranged that the distance normally between said bearing surfaces is less than the width of the rail base, one of said arms having spaced lips adapted to engage the respective top and bottom surfaces of the adjacent rail base flange and the other of said arms having a lip adapted to bear on the top surface of the rail base flange adjacent thereto but being open at the bottom to permit the said bearing surfaces to exert a maximum gripping force on the rail base, for the purpose specified.

13. A rail anchor comprising means adapted to extend transversely under a rail base and having upwardly extending return disposed arm means at one end and upwardly extending angularly disposed arm means at the other end, said arm means having bearing surfaces adapted to grip the edges of the respective rail base flanges and being so arranged that when the bearing surface on said return disposed portion is in engagement with the edge of one of the rail base flanges, the angularly disposed arm means with its bearing surface extends above and over the other rail base flange whereby the end of the device having said last-named arm means must be forced down relatively to the rail base to bring the bearing surface thereon into engagement with the edge of the base flange adjacent thereto.

14. A one-piece rail anchor formed of resilient material and comprising a portion adapted to extend transversely under a rail base and having an upwardly extending return disposed arm at one end and an angularly disposed arm at the other end, said arms having bearing surfaces adapted to grip the edges of the respective rail base

flanges, said arms being so arranged that when the bearing surface on said return disposed portion is in engagement with the edge of one of the rail base flanges, the angularly disposed arm with its bearing surface extends above and over the other rail base flange whereby the end of the device having said last-named arm must be forced down relatively to the rail base to bring the bearing surface thereon into engagement with the edge of the base flange adjacent thereto.

15. A rail anchor comprising means adapted to extend transversely under a rail base and having upwardly extending arm means at one end thereof and upwardly extending arm means at the other end thereof, said arm means having bearing surfaces adapted to grip the edges of the respective rail base flanges, said arm means and bearing surfaces being so arranged that in applying the device to a rail said first-named arm means is hooked over one rail base flange and the device shifted laterally to bring the edge of the other base flange into the bight between the second-named arm means and the transversely extending means, the bearing surface on the first-named arm means being then brought into engagement with the edge of the base flange adjacent thereto and then the opposite end of the device is forced down relatively to the rail base to bring the bearing surface on the second-named arm means into engagement with the edge of the base flange adjacent to it.

35. 16. A one-piece rail anchor formed of resilient material and comprising a portion adapted to extend transversely under a rail base and having an upwardly extending arm at one end thereof and an upwardly extending arm at the other end thereof, said arms having bearing surfaces adapted to grip the edges of the respective rail base flanges, said arms and bearing surfaces being so arranged that in applying the device to a rail the first-named arm is hooked over one rail base flange and the device shifted laterally to bring the edge of the other base flange into the bight between the second-named arm and the transversely extending portion, the bearing surface on the first-named arm being then brought into engagement with the edge of the base flange adjacent thereto and then the opposite end of the device is forced down relatively to the rail base to bring the bearing surface on the second-named arm into engagement with the edge of the base flange adjacent to it.

17. A rail anchor comprising means adapted to extend transversely under a rail base and having upwardly extending return disposed arm means at one end and upwardly extending angularly disposed arm means at the other end, said arm means having bearing surfaces adapted to grip the edges of the respective rail base flanges,

said arm means and bearing surfaces being so arranged that in applying the device to a rail the return disposed arm means is hooked over one rail base flange and the device shifted laterally to bring the edge of the other base flange into the bight between the angularly disposed arm means and the transversely extending means, the bearing surface on the return disposed arm means being then brought into engagement with the edge of the base flange adjacent thereto and then the opposite end of the device is forced down relatively to the rail base to bring the bearing surface on the angularly disposed arm means into engagement with the edge of the base flange adjacent to it.

18. A one-piece rail anchor formed of resilient material and comprising a portion adapted to extend transversely under a rail base and having an upwardly extending return disposed arm at one end and an upwardly extending angularly disposed arm at the other end, said arms having bearing surfaces adapted to grip the edges of the respective rail base flanges, said arms and bearing surfaces being so arranged that in applying the device to a rail the return disposed arm is hooked over one rail base flange and the device shifted laterally to bring the edge of the other base flange into the bight between the angularly disposed arm and the transversely extending portion, the bearing surface on the return disposed arm being then brought into engagement with the edge of the base flange adjacent thereto and then the opposite end of the device is forced down relatively to the rail base to bring the bearing surface on the angularly disposed arm into engagement with the edge of the base flange adjacent to it.

19. A one-piece rail anchor formed of resilient material and comprising a portion adapted to extend transversely under a rail base and having an upwardly extending arm at each end, said arms having bearing surfaces adapted to grip the edges of the respective rail base flanges, said arms being so arranged that the distance normally between said bearing surfaces is less than the width of the rail base while the distance between each bearing surface and the bight between the arm on the opposite end of the device and said transversely extending portion is greater than the width of the rail base.

20. A rail anchor comprising means adapted to extend transversely under a rail base and having upwardly extending return disposed arm means at one end and upwardly extending angularly disposed arm means at the other end, said arm means having bearing surfaces adapted to grip the edges of the respective rail base flanges, said arm means being so arranged that the

- 8 distance normally between said bearing surfaces is less than the width of the rail base while the distance between each bearing surface and the bight between the arm means 5 on the opposite end of the device and said transversely extending means is greater than the width of the rail base.
21. A one-piece rail anchor formed of resilient material and comprising a portion 10 adapted to extend transversely under a rail base and having an upwardly extending return disposed arm at one end and an angularly disposed arm at the other end, said arms having bearing surfaces adapted to 15 grip the edges of the respective rail base flanges, said arms being so arranged that the distance normally between said bearing surfaces is less than the width of the rail base while the distance between each bearing 20 surface and the bight between the arm on the opposite end of the device and said transversely extending portion is greater than the width of the rail base.
22. A rail anchor comprising means 25 adapted to extend transversely under a rail base and having upwardly extending arm means at one end provided with a bearing surface adapted to grip the edge of one of the rail base flanges and with upper and 30 lower lip means adapted to engage the respective top and bottom surfaces of said flange, said transverse means having upwardly extending arm means at the other end provided with a bearing surface adapted 35 to grip the edge of the other rail base flange and with lip means adapted to engage the top surface of said last-named flange, said arm means being so arranged that the distance normally between said bearing surfaces 40 is less than the width of the rail base while the distances between said lower lip means and the bight formed by said second-named arm means with said transverse means and between said third-named lip means and the bight formed by said first-named arm means with said transverse means are greater than the width of said rail base.
23. A one-piece rail anchor formed of resilient material and comprising a portion 50 adapted to extend transversely under a rail base and having an upwardly extending arm at one end provided with a bearing surface adapted to grip the edge of one of the rail base flanges and with upper and lower 55 lips adapted to engage the respective top and bottom surfaces of said flange, said transverse portion having an upwardly extending arm at the other end provided with a bearing surface adapted to grip the edge 60 of the other rail base flange and with a lip adapted to engage the top surface of said last-named flange, said arms being so arranged that the distance normally between said bearing surfaces is less than the width of the rail base while the distances between 65 said lower lip and the bight formed by said second-named arm with said transverse portion and between said third-named lip and the bight formed by said first-named arm with said transverse portion are greater than the width of said rail base.
24. A rail anchor comprising means adapted to extend transversely under a rail base and having upwardly extending return disposed arm means at one end provided with a bearing surface adapted to grip the edge of one of the rail base flanges and with upper and lower lip means adapted to engage the respective top and bottom surfaces of said flange, said transverse means having upwardly extending angularly disposed arm means at the other end provided with a bearing surface adapted to grip the edge of the other rail base flange and with lip means adapted to engage the top surface of said last-named flange, said arm means being so arranged that the distance normally between said bearing surfaces is less than the width of the rail base while the distances between said lower lip and the bight formed by said second-named arm with said transverse means and between said third-named lip and the bight formed by said first-named arm with said transverse means are greater than the width of said rail base.
25. A one-piece rail anchor formed of resilient material and comprising a portion adapted to extend transversely under a rail base and having an upwardly extending return disposed arm at one end provided with a bearing surface adapted to grip the edge of one of the rail base flanges and with upper and lower lips adapted to engage the respective top and bottom surfaces of said flange, said transverse portion having an upwardly extending angularly disposed arm at the other end provided with a bearing surface adapted to grip the edge of the other rail base flange and with a lip adapted to engage the top surface of said last-named flange, said arms being so arranged that the distance normally between said bearing surfaces is less than the width of the rail base while the distances between said lower lip and the bight formed by said second-named arm with said transverse portion and between said third-named lip and the bight formed by said first-named arm with said transverse portion are greater than the width of said rail base.
26. A rail anchor comprising means adapted to extend transversely under a rail base and having upwardly extending return disposed arm means at one end and upwardly extending angularly disposed arm means at the other end, said arm means having bearing surfaces adapted to grip the edges of the respective rail base flanges, said arm means being so arranged and said

respective bearing surfaces being so located thereon that the distance normally between said bearing surfaces is less than the width of the rail base and after application of the 5 device to the rail there is a substantial space between the rail base and said transverse means.

27. A one-piece rail anchor formed of resilient material and comprising a portion 10 adapted to extend transversely under a rail base and having an upwardly extending return disposed arm at one end and an angularly disposed arm at the other end, said arms having bearing surfaces adapted to 15 grip the edges of the respective rail base flanges, said arms being so arranged and said respective bearing surfaces being so located thereon that the distance normally between said bearing surfaces is less than the 20 width of the rail base and after application of the device to the rail there is a substantial space between the rail base and said transverse portion.

28. A rail anchor comprising means 25 adapted to extend transversely under a rail base and provided at one end with an arm adapted to be engaged with one flange of a rail base and provided at the other end with an arm adapted to be moved vertically into 30 operative engagement with the opposite

flange of said base; said arms being so disposed with relation to each other as to be spread apart during said upward movement of said arm and restrained from any appreciable inward spring movement of said arm when the anchor reaches its normal operative position on the rail.

29. A rail anchor comprising means adapted to extend transversely under a rail base and provided at opposite ends with 40 rail base gripping means adapted to be brought into normal gripping engagement with the rail base by vertical movement of the anchor; said gripping means being so disposed with relation to each other as to be 45 spread apart during the application of the device to a rail and to be brought to their normal gripping position without snapping engagement with the rail.

30. A rail anchor comprising means 50 adapted to extend transversely under a rail base and having inwardly extending arms adapted to be distorted into gripping engagement with the vertical edges of said base at opposite sides of the rail, said arms 55 being so arranged that the anchor, when in its normal applied position on a rail, is subjected to substantially its maximum distortion.

ROLANDIS A. BLAIR.
